CLAIM

The ornamental design for a hi-fi mini audio system with wireless technology for MP3 player, as shown.

DESCRIPTION

FIG. 1 is a top plan view of a hi-fi mini audio system with wireless technology for MP3 player showing my new design;

FIG. 2 is a left side elevational view thereof;

FIG. 3 is a front elevational view thereof;

FIG. 4 is a right side elevational view thereof;

FIG. 5 is a rear elevational view thereof;

FIG. 6 is a bottom plan view thereof;

FIG. 7 is a right front side perspective view thereof; and,

FIG. 8 is a right rear side perspective view thereof.
